(57) **CLAIM**

The ornamental design for a headlamp bezel, as shown and described.

DESCRIPTION

FIG. 1 is a front perspective view of a headlamp bezel according to our new design;

FIG. 2 is a front elevational view of the headlamp bezel of FIG. 1;

FIG. 3 is a top plan view of the headlamp bezel of FIG. 1; and, FIG. 4 is a left side view of headlamp bezel of FIG. 1.

The rear of the headlamp bezel is unornamented.

FIGS. 1-4 illustrate a first embodiment of our novel design suitable for use on the left side of a vehicle. Our novel design also includes a second embodiment suitable for use on the right side of a vehicle, which is mirrored symmetrical to FIGS. 1-4 and therefore not separately illustrated.

The broken lines shown in the drawings illustrate portions of the headlamp bezel that form no part of the claimed design.
